UNITED STATES PATENT OFFICE.

JOHN M. M. GREGORY, OF DURHAM, NORTH CAROLINA.

RECEPTACLE-CLOSURE.

1,365,398.

Specification of Letters Patent. Patented Jan. 11, 1921.

Application filed January 29, 1919. Serial No. 273,810.

To all whom it may concern:

Be it known that I, JOHN M. M. GREGORY, a citizen of the United States, residing at Durham, in the county of Durham and State 5 of North Carolina, have invented a new and useful Receptacle-Closure, of which the following is a specification.

This invention relates to receptacle closures and more particularly to closure 10 adapted for use in connection with tooth-powder receptacles or containers. Existing devices of this character have proven unsatisfactory because of the great waste of tooth-powder entailed in their employment. 15 The outlet apertures of these receptacles are usually so restricted in dimensions that it is necessary for the user to repeatedly shake the receptacle before the desired amount of powder is deposited on the tooth brush. 20 This operation obviously causes a considerable amount of the powder to be wasted during each effort to apply it to the tooth-brush. If the outlet aperture of these receptacles are made large enough to allow 25 the powder to flow freely from the receptacle without shaking, then an appreciable amount of the powder is wasted in the user's effort to discontinue the flow of powder from the receptacle after the required amount has 30 been deposited on the brush. Again, it is impossible to obtain a uniform deposit of powder on the brush when employing the existing container, since the powder is discharged from the receptacle only when it is 35 shaken, therefore causing the powder to be deposited on the brush in separate heaps instead of a uniform distribution.

An object of this invention is to provide 40 means for uniformly distributing or depositing tooth powder on a tooth-brush without any waste of the powder during the depositing operation.

Another object of this invention is to provide 45 a receptacle closure of generally improved construction, whereby the device will be simple, durable and inexpensive in construction, as well as, convenient, practical, serviceable and efficient in its use.

The invention has been illustrated in the 50 accompanying drawings, wherein:

Figure 1 is a side elevation of the invention, depicting it in use.

Fig. 2 is a longitudinal section taken 55 through the closure construction, showing it in open position.

Fig. 3 is a similar view, but showing the closed position.

Fig. 4 is a transverse sectional view taken on the line 4—4 of Fig. 3.

Fig. 5 is a perspective view of the closure 60 member.

Fig. 6 is a longitudinal sectional view taken through a modified form of the invention.

Fig. 7 is a similar view taken through 65 another slight modification.

Referring to the drawing, there is shown a container or receptacle 1 having a reduced tubular member or neck 2 extending therefrom. A cylindrical member 3 is soldered or otherwise secured to the inner surface of the neck 2, this cylindrical member has an end wall or partition 4 formed at its inner end. Portions of the side and end walls of the cylindrical member 3 are pressed inwardly to provide a plurality of longitudinal channels or recesses 5, that extend from the partition 4 and along the cylindrical member 3 to a point adjacent its outer end. 70

A sleeve 6 is mounted for rotation upon the cylindrical member 3, but is held against longitudinal movement with respect to the cylindrical member by interfitting annular grooves 7 and 8 formed in and adjacent the outer ends of the sleeve 6 and cylindrical 75 member 3 respectively. The outer end of the sleeve 6 is closed by an end wall 9, which extends laterally beyond the periphery of the sleeve 6 to provide a manipulating bead or member 10 for this sleeve; and the inner end of the sleeve 6 abuts against the outer end of the neck 2. A longitudinal slot 11 is formed in the sleeve 6, and is adapted to coöperate with the longitudinal recesses 5 to provide an outlet for the contents of the 80 container 1, the length of the slot 11 approximates the length of the bristle portion of an ordinary tooth-brush. 85

In use, the reduced neck or end of the container is held downwardly, so that the powder within the container 1 will flow or gravitate into the longitudinal recesses 5, which, at all times, communicate with the interior of the container. Then the container 1 is held in a horizontal position, and the sleeve 6 is rotated until its longitudinal slot 11 registers with the uppermost one of the recesses 5, thereby uncovering this recess, as shown in Fig. 4. Now the contents of this recess may be uniformly deposited 95 100 105 110

on the bristles of a tooth-brush by simply turning the container 1 about its longitudinal axis until this recess is in its lower-most position where the powder will flow freely therefrom, as indicated in Fig. 1. After this, the container 1 may be closed or sealed by turning the sleeve 6 so that its longitudinal slot 11 lies between any two of the recesses 5, which causes the wall of the sleeve 6 to cover all the recesses 5. The recesses 5 may be formed of different sizes and shapes to best conform to the requirement of different manufacturers.

A slight modification is disclosed in Fig. 6, in which the neck of the container 1 is extended to form a sleeve 6', having a longitudinal slot 11', and a cylindrical member 3' is rotatably mounted within the sleeve 6'. Longitudinal recesses 5' are formed in the cylindrical member 3', and the sleeve 6' and cylindrical member 3' are held against longitudinal movement with respect to each other by interfitting annular grooves 7' and 8'. The outer end of the cylinder 3' is closed by an end wall 9', which extends laterally beyond the periphery of the sleeve 6' where it is turned about a flange extending laterally from the cylindrical member, to provide a manipulating bead 10' for the cylindrical member. This form operates in the same manner as that hereinbefore described, except that the cylindrical member 3' is rotated in lieu of the sleeve member.

Fig. 7 shows another slight modification comprising a sleeve 6'' having an annular, laterally-extending flange 6'' formed at its outer end. A cylindrical member 3'' is rotatably mounted within the sleeve 6'', and has longitudinal recesses 5'' formed therein and adapted to coöperate with a longitudinal slot 11'' formed in the sleeve 6''. The outer end of the cylindrical member 3'' is provided with an end wall or closure 9'', which extends laterally beyond the per-

iphery of the sleeve 6'' and turns about 45 the flange 6'' formed at the outer end of the sleeve 6. By this arrangement a manipulating bead 10'' is formed to provide means for rotating the cylindrical member 3'', which bead, also, holds the sleeve 6'' and cylindrical 3'' against longitudinal or axial movement with respect to each other, but permits the cylindrical member 3'' to freely rotate within the sleeve 6''.

Having thus described my invention what 55 is claimed as new is:—

A device of the class described including a container, a cylindrical member longitudinally disposed with respect to the container and having longitudinally disposed recesses 60 extending inwardly from the periphery thereof, said recesses communicating with the interior of the container, a partition formed at that end of the cylindrical member which is positioned adjacent the container and adapted to separate the interior of the cylindrical member from the interior of the container, a sleeve forming a neck for the container and having a longitudinally disposed slot formed therein, a manipulating 65 bead adapted to provide means for causing a relative rotation between the said cylindrical member and sleeve in order to move the longitudinal recesses and longitudinal slots into and out of registration 70 with each other, thereby providing an outlet and closure for the container, and means for securing the sleeve and cylindrical member against longitudinal movement with 75 respect to each other.

In testimony that I claim the foregoing as my own, I have hereto affixed my signature in the presence of two witnesses.

JOHN M. M. GREGORY.
